(57) **CLAIM**

The ornamental design for a mounting module for traffic lighting system, as shown and described.

DESCRIPTION

FIG. 1 is an oblique view, taken from the front and from above, of a mounting module for traffic lighting system showing my new design;

FIG. 2 is front elevation view thereof, taken from the rear;

FIG. 3 is a left side view thereof;

FIG. 4 is a right side elevation view thereof;

FIG. 5 is a top plan view thereof;

FIG. 6 is a rear elevation view thereof; and,

FIG. 7 is a bottom plan view thereof.

The portions of the mounting module for traffic lighting system shown in broken lines form no part of the claimed design.
